US00D521851S

(12) **United States Design Patent** (10) **Patent No.:** **US D521,851 S**
Smart (45) **Date of Patent:** **** May 30, 2006**

(54) **GAS TUBE BLOCK SUPPORT**

(76) Inventor: **Kenneth Smart**, 14167 Oasis Rd.,
Caldwell, ID (US) 83607

(**) Term: **14 Years**

(21) Appl. No.: **29/201,125**

(22) Filed: **Mar. 9, 2004**

(51) LOC (8) Cl. **08-05**

(52) U.S. Cl. **D8/354**

(58) **Field of Classification Search** D8/349,
D8/354; 248/49, 346.01, 346.06

See application file for complete search history.

(57) **CLAIM**

The ornamental design for a gas tube block support, as shown and described.

DESCRIPTION

FIG. 1 is a representational perspective view of the invention;

FIG. 2 is a representational side view of a first side of the invention;

FIG. 3 is a representational front view of the invention;

FIG. 4 is a representational side view of a second side of the invention;

FIG. 5 is a representational back view of the invention;

FIG. 6 is a representational bottom view of the invention; and,

FIG. 7 is a representational top view of the invention.

1 Claim, 7 Drawing Sheets

FIG. 1

FIG. 2

FIG. 3

FIG. 4

FIG. 5

FIG. 6
